No. 36,816.

Patented February 23, 1904.

UNITED STATES PATENT OFFICE.

JAMES MADDOCK, OF ALSAGER, ENGLAND, ASSIGNOR TO MADDOCK & MILLER, A CORPORATION OF NEW YORK.

DESIGN FOR A DISH.

SPECIFICATION forming part of Design No. 36,816, dated February 23, 1904.

Application filed January 20, 1904. Serial No. 189,916. Term of patent 3½ years.

To all whom it may concern:

Be it known that I, JAMES MADDOCK, a citizen of Great Britain, and a resident of Alsager, in the county of Chester, England, have 5 invented a new, original, and ornamental Design for a Dish.

The figure is a plan view of the dish, showing my design.

What I claim is—

The ornamental design for a dish, as shown. to

JAMES MADDOCK.
